The ornamental design for a compressed natural gas manifold, as shown and described.

DESCRIPTION

FIG. 1 is a perspective view of an embodiment of a compressed natural gas (CNG) manifold;

FIG. 2 is a perspective view of the embodiment of the CNG manifold of FIG. 1;

FIG. 3 is a side view of the CNG manifold of FIG. 1; and,

FIG. 4 is a front view of the CNG manifold of FIG. 1.
In the drawings, the broken lines depict portions of the design that form no part of the claimed design.**1 Claim, 1 Drawing Sheet**| (56)	References Cited
